LOW WATER CUTOFF

Oscar F. Carlson, Kenilworth, Ill., assignor of one-half to Oscar F. Carlson Company, Chicago, Ill., a corporation of Illinois, and one-half to Everett N. McDonnell, Chicago, Ill.

Application September 6, 1938, Serial No. 228,566

3 Claims. (Cl. 200—84)

This invention relates generally to control devices for boilers and the like and is more particularly concerned with control devices that respond to liquid level for controlling water feeders, burners, fuel supply, and the like.

The object and general nature of this invention resides in the provision of a low water cutoff that is responsive to the liquid level in the boiler and may be employed for controlling a water feeder for maintaining substantially constant water level in the boiler and also shutting down the burner if the liquid level falls too low. More specifically, it is a feature of this invention to provide a float and float chamber with a switch assembly which includes two units, both controlled by the float and one acting to control the water feeder while the other is arranged to control the burner.

Another feature of this invention resides in the provision of a float chamber which is formed, at least partially, by a sleeve or similar part that threads directly into the boiler at the water level thereof and does not require any other connections to the boiler for its installation. Another feature of this invention is an improved form of screen for the float chamber.

These and other objects and advantages of the present invention will be apparent to those skilled in the art after a consideration of the following detailed description, taken in conjunction with the accompanying drawings.

In the drawings:

Figure 1 is a longitudinal vertical section taken through a boiler control device embodying the principles of the present invention;

Figure 2 is an elevation of the switch assembly as it appears when detached from the float chamber and the outer switch housing, corresponding generally to a view along the line 2—2 of Figure 1;

Figure 3 is an end view taken generally along the line 3—3 of Figure 1 but with the conduit cover removed;

Figure 4 is a section taken through the switch assembly generally along the line 4—4 of Figures 2 and 6;

Figure 5 is a section taken along the line 5—5 of Figures 2, 4, and 6, and showing, in addition, the operating lever for the two switch units;

Figure 6 is a section taken along the line 6—6 of Figure 4;

Figure 7 is a perspective view of one of the adjusting screws;

Figure 8 is a section taken along the line 8—8 of Figure 6;

Figure 9 is a perspective view of one of the four screen sections which make up a screen at the inner end of the float chamber;

Figure 10 is a view of the screen disc that holds the screen sections of Figure 9 in position;

Figure 11 is a fragmentary view showing the manner of inserting each of the four screen sections;

Figure 12 is a perspective view of one of the two brackets securing the switch unit to the float chamber; and

Figures 13 and 14 show a modified form of float chamber and screen.

Referring now to the drawings, particularly to Figure 1, the boiler or other device on which the control unit is mounted is indicated in its entirety by the reference numeral 1 and includes a wall 2 having a screw threaded opening 3 formed therein substantially at the water level, indicated at 4, of the boiler. The control device 20 in which the principles of the present invention have been embodied is indicated in its entirety by the reference numeral 6, and consists generally of a float chamber in which the float is movably disposed and a switch assembly or other controlling device mounted thereon.

The float chamber is indicated at 7 and consists of a casing 8 and a sleeve 9 rotatable with respect to the casing 8. The latter is disposed generally vertically and has an upper threaded opening 10 closed by a plug 11 and a lower closure plate 12 fastened by cap screws 13 or the like. The plate 12 has a threaded opening 14 which may be closed by a plug 15. It will be noted that the lower portion of the casing 8 extends below the sleeve 9 so that there is little likelihood of any sediment or other deposits collecting in the sleeve. The plug 14 may be removed to drain the casing 8, but if desired the entire plate 12 may be removed. The casing 8 is also provided with a recess 16 which receives the flange 17 that is formed on the outer end of the sleeve 9. The inner end of the latter is threaded as at 18 and is adapted to be screwed into the opening 3 of the boiler wall in leak-tight relation. A gasket 19 is disposed between the flange 17 on the sleeve 9 and the socket or recess 16 of the casing 8. A clamping ring 21 is disposed about the sleeve 9 and bears against the flange 17 thereof to hold the same firmly to the casing 8. The clamping ring 21 is tightened by any suitable means, such as clamping screws 22 extending through a flange 23 on the casing 8 surrounding the socket 16 and threaded into the clamping ring 21.

When the clamping ring 21 is loosened, the sleeve 9 may be turned with respect to the casing 8, thereby facilitating screwing the sleeve into the boiler 2. The sleeve 9 has a polygonal wrench receiving section 25, and the inner end of the sleeve 9 is reduced, as at 27, and provided with openings 27a to receive a screen which is indicated in its entirety by the reference numeral 28 and which preferably extends into the boiler, as indicated. The screen 28 comprises four sections 28a, each of which is provided with an inwardly bent tongue 29 and projecting lugs 29a, as best shown in Figure 9. Also, each screen section 28a includes a pair of slots 30 formed in the end of screen section 28a opposite the tongue 29, and one or more openings 30a. The screen 28 also includes a circular disc 31 provided with slots 31a and pairs of tongues 32, as best shown in Figure 10. The screen 28 is capable of being assembled easily and quickly on the inner end 27 of the sleeve 9 in the manner indicated in Figure 11. That is, each of the four screen sections 28a is individually mounted by inserting the tongue 29 into the associated sleeve opening 27a with the screen section 28a in the position shown in Figure 11 so that the end portion of the tongue 29 engages underneath one edge of the opening 27a, as best shown in Figure 1, when the screen section 28 is swung into the position shown in Figure 1. The disc 31 with the pairs of tongues 32 is held in position by engaging the tongues of each pair into the adjacent slots 30 of the four screen sections 28a, and then bending over the tongues 32, thus holding the four screen sections 28a in cylindrical relation and also holding the screen end 31 in place. The openings 30a and 31a provide for a free flow of water between the boiler and the float chamber 7.

A float 33 is movably mounted within the float chamber 7 and is of the tubular elongated type. At its inner end the float 33 extends through the sleeve 9 and partially into the space within the screen 28, and at its outer end the float 33 carries a float arm 35 which is secured to the head of the float in any suitable manner, as by a screw 36 that extends through the head of the float, indicated at 37, and into a tapped opening in the inner end of the float arm 35. The head or cap 37 of the float is secured to the main body thereof in any suitable manner, as by soldering or the like.

One end of the casing 8 is open, as at 40, and receives an end plate 41 which is clamped to the casing 8 by a clamping ring 42, generally U-shaped in section having inner and outer flanges 42a and 42b, and a plurality of cap screws 43. The central portion of the end plate 41 is cupped, as at 44, and receives a ring 45 having a central opening 46 and provided with a pair of lugs or ears 47. A pivot pin 48 is carried by the ears 47 and, in turn, extends through an opening in the float arm 35 and supports the float 33 for pivotal movement in the float chamber 7. The supporting ring 45 is secured in any suitable manner, as by soldering or the like, to the cupped section 44 of the end plate 41, the latter having a central opening 51 registering with the opening 46 in the ring 45.

The outer end of the float arm extends through the openings 46 and 51 and into the space beyond the end plate 41, and in order to provide a seal between the float 33 and the float chamber a bellows 53 is disposed about the float arm 35 and

its supporting lugs 47. The inner end of the bellows 53 is disposed between a washer 55 and the end of the float arm 35, whereby when the attaching screw 36 is tightened the bellows is secured to the outer end of the float 33. The outer end of the bellows 53 is secured by soldering or otherwise to the ring 45 and the end plate 41. Thus, one end of the bellows 53 is sealed to the float chamber and the other end to the float 33, whereby the latter may move vertically in response to changes in the water level in the boiler 1 with considerable freedom of movement about the pivot pin 48.

The switch assembly that is controlled by the float 33 is indicated in its entirety by the reference numeral 60 and is disposed within and carried by a shell 61, one wall of which is open, as at 62, and the other end of the shell 61 receives the channel ring 42 which clamps the plate 41 to the float chamber. The switch assembly 60 includes a casing 65 that is formed by a base member 66 and a cover 67, both being formed of insulating material, as best shown in Figures 4, 5 and 6. The base 66 includes at one side thereof a raised portion 68 around which the edge of the cover 67 fits, and the opposite side of the base 66 is also provided with a raised section 69 which is recessed at 71 to receive terminals referred to below. The cover 67 of the switch casing 65 is provided with an elongated boss 73 which is apertured, as at 74 and 75 and recessed, as at 77, forming two upstanding side walls 78. The base 66 and the cover 67 are made of insulating material, and a pair of screws 79 pass upwardly through the base and are threaded into tapped openings in bosses 80 formed on the cover 67 to secure the cover and base together.

A pivot pin 81 is disposed in suitable openings in the recess walls 78, and a lever 82 has a portion 40 disposed within the recess 77 and pivotally mounted on the pin 81. The lever 82 has a recess 83 and lateral arm sections 84 disposed generally in the plane of the boss 73. A pair of arms 87 and 88 are also pivotally mounted on the pin 81 and 45 formed to lie alongside the sections 84 of the lever 82. Each of the arms 87 and 88 is provided with a laterally extended lug 89 disposed over the bores 74 and 75 formed in the cover 67. Plungers 91 and 92 are disposed in said bores and are engaged by the lugs 89 on the arms 87 and 88.

Each of the arms 87 and 88 may be fixed in adjusted position relative to the lever 82 independently of the other arm. Each adjusting means includes a cam screw 94 which is best 55 shown in Figure 7. Each cam screw 94 includes a head 95 and a threaded shank 96 formed integrally with and arranged in eccentric relation with respect to the head 95. The lever 82 is provided with two screw threaded openings receiving the cam screws 94, and each cam screw carries a lock nut 97. The head 95 of each of the cam screws is generally cylindrical and is received within an elongated slot 98 formed in each of the arms 87 and 88. Thus, when the lock nut 97 of either cam screw is loosened, the screw may be turned, and due to the eccentric relation between the shank and the head of the screw, turning the screw 95 adjusts the position of the arm 70 relative to the lever. After the arm is adjusted, the lock nut 97 may be tightened to retain the desired adjustment. It will be noted that adjustment of either of the arms 87 and 88 takes place about the pivot 81, which is a pivot about which 75

the lever 82 swings, and that each adjustment is independent of the other.

The lever 82 is adapted to be actuated by the extended end of the float arm 35. The float arm 5 35 carries a pivot 101 upon which a roller 102 is pivoted, and when the switch mechanism 60 is in place, the recess 83 of the lever 82 is disposed on opposite sides of the roller 102, as best shown in Figure 1, whereby vertical swinging movement of the 10 float 33 will swing the lever 82 in one direction or the other, and swinging movement of the lever 82 depresses one or the other of the plungers 91 and 92. The switch units controlled by the plungers 91 and 92 will now be described.

15 As best shown in Figure 6, the housing 65 encloses two separate switch units 105 and 106 which are arranged along side one another but in opposite relation and generally transverse with respect to the plane of the operating lever 82 20 which controls both of the switch units. The switch units 105 and 106 are substantially identical so that a description of one will suffice, corresponding parts of the two units being indicated by the same reference numerals.

25 Referring now to Figure 4, the base 66 carries a stationary terminal 110 that includes a sleeve 111 to which the horizontal portion 112 of a bracket 113 is riveted or otherwise fixed in a suitable manner. The sleeve 111 is threaded to receive a 30 screw 114 under the head of which a flanged terminal washer 116 is disposed. Each washer has one or more notches 117 to accommodate the wire or conductor that is fastened by the screw 114 to the terminal 110. The base 66 also carries a stationary contact structure 120 which comprises a sleeve 121 internally threaded to receive a terminal screw 122 substantially identical with the screw 114 described above. Underneath the head of the screw 122 is a flanged terminal washer 123 40 having a conductor receiving recess 124. The sleeve 121 carries an apertured head 126 in which a contact element 127 is fixed, as by being riveted therein. Underneath the head 126 of the sleeve 121 is a plate 128 having an end 129 extending 45 over the intermediate portion of the small horseshoe magnet 131, the latter being seated in a recess 132 formed in the base 66 to receive it. The two poles of the magnet 131 are indicated at 133 and 134 (Figure 5). The magnet 131 influences 50 a movable switch element which will now be described.

The bracket 113, which is fixed to the base by the terminal 111, includes a standard section 138 which is apertured to receive a screw 139 which 55 is threaded into a clip 141 and secures the upwardly bent end 142 of a spring arm 143. The opposite end of the spring arm 143 carries a contact element 145 which has a shank 146 extending through an aperture in the spring arm 143 60 and through an aperture in an armature 147. The outer end of the latter has a tongue 148 bent over the outer end of the spring arm 143 to secure the firm attachment of the armature 147 to the outer end of the spring arm 143. As best shown 65 in Figure 8, portions 149 of the armature are pressed into openings 150 in the arm 143, thereby preventing any relative movement between the arm and the armature.

The armature 147 is disposed, as best shown in 70 Figure 4, directly above the magnet 131, close enough to the magnet 131 so that when the contacts 127 and 145 are in engagement the magnet exerts an appreciable pull on the armature to hold the contacts in engagement until a force is exerted through the spring arm 143 that is sufficient

to overcome the pull of the magnet, whereupon the contacts 127 and 145 separate with a quick or snap action. The movement of the outer end of the spring arm 143 is limited by its contact with the abutment portion 67a formed on the 5 casing cover 67.

The means acting through the spring arm 143 to separate the contacts consists of a lever 151 which is generally U-shaped in section and has an extended portion 152 engaged by the head of the 10 associated plunger 91 or 92. The sides of the member 151 are extended in the form of arms 154 and 155 and receive a pivot pin 156 which is supported in a pair of ears 157 and 158 which extend upwardly from and form a part of the 15 bracket 113. The spring arm 143 passes between the arm sections 154 and 155, and the ends of the arm sections 154 and 155 are apertured to rotatably receive the reduced ends of a roller 160 that lies underneath the spring arm 143 adjacent the 20 point where the latter is anchored to the standard 138.

The boss or raised portion 68 on the base 66 and the cover 57 are preferably rectangular in formation, thereby facilitating a proper assembly 25 of the switch mechanism and insuring that the plungers 91 and 92 will be in the proper position relative to their operating levers 151 and the abutment stops 67a for the spring arms, regardless as to which way the cover is applied to the 30 base.

The shell 61 carries an extension 165 having an aperture 166 therein and the extension 165 extends from one edge of the opening 62. The opening 62 is closed by a terminal cover 167 35 which encloses the exposed face of the switch assembly 60 and has a flanged portion 168. The portion 168 has an aperture 169 which receives a screw 171 by which the cover 167 is attached to the shell 61. The shell 61 has a tapped open- 40 ing 172 to receive the screw 171.

The switch assembly 60 is secured to the float chamber by a pair of brackets 175, best shown in Figures 1, 2, 3, and 12. Each bracket consists of a generally U-shaped strap member having 45 an intermediate section 177, fastened to the base 66 by a pair of screws 178, and a pair of arms 179 which extending along the switch case 65 (Figure 1) and terminate in outwardly bent arcuate portions 181 which are arranged to fit between the flanges 42a and 42b of the clamping ring 42 and are apertured, as at 182 (Figure 2), to receive screws 183 (Figure 3) which are threaded into tapped openings in the clamping ring 42 and by which the brackets are fixed to the 55 float chamber to hold the actuating lever 82 in operative relation with the roller 102 at the outer end of the float arm 35. The outer portion or flange of the base 66 is provided with a pair of apertures 184 (Figure 2) to receive a pair of 60 screws 185 (Figure 3) by which the shell 61 is fastened in place about the switch assembly 60. The screws 185 may thread into the base 66 or may extend to and thread into the ring 42. The conductors (not shown) from the switch terminals 110 and 120 extend outwardly through the openings 166 to the units to be controlled, and to simplify the connections the terminal 110 (Figure 3) of the switch unit 106 may be connected by a copper strip 186 to the terminal 120 70 of the other switch unit 105.

Preferably the shell 61 may be secured in any one of four positions so as to lead the conductors in the desired direction. To this end the base 66 has recesses or holes 187 (Figures 2 and 3) 75

and the intermediate sections 177 of the brackets 175 have holes 188 (Figure 2) to receive the attaching screws 185 when the shell 61 is turned 90° from the position shown. The shell 61 may, 5 of course, be turned 180° by using the holes 184 in the base 66.

In operation, as the float 33 rises and falls in response to variations in the water level in the boiler 1, the outer end of the float arm 35 swings 10 the actuating lever 82 about its pivot 81. The movement of the lever 82 acts through the arm sections 87 and 88 to actuate one or the other of the plungers 91 and 92, the heads of which engage the lateral arm sections 89. For example, 15 if the liquid level in the boiler 1 falls the downward movement of the float 33 swings the float arm 35 in a counterclockwise direction (Figure 1) about the pivot 48, which swings the actuating lever 82 in a clockwise direction about its pivot 20 81 on the switch housing 65. This movement of the lever 82 depresses the plunger 92 and swings the lever 151 about its pivot support 156 (Figure 4), which is in a clockwise direction, and causes the roller 160 to bear upwardly against the spring 25 arm 143 adjacent its inner or anchored end. It will be remembered, however, that the magnet 131 exerts a pull on the armature 147 to hold the contacts 127 and 145 in engagement with a certain amount of force, so that the movement of 30 the roller 160 against the spring arm 143 flexes the latter until the spring arm exerts a force that is sufficient to overcome the pull of the magnet 131. As soon as the force of the latter is overcome, the armature is pulled away from the magnet 35 and the spring arm 143 separates the contacts 127 and 145 very quickly and with a snap action.

When the liquid level in the boiler 1 rises, the upward movement of the float 33 swings the lever 82 in the other direction, counterclockwise as 40 viewed in Figures 1 and 5, which first relaxes the pressure against the plunger 92, permitting the resilience of the spring 143 to bring the contacts 145 and 127 of the switch unit 105 into engagement, and then the other plunger 91 of the other 45 switch unit 106 will be depressed, snapping the contacts 127 and 145 of that unit into open position.

The two switch units 105 and 106, controlled by the float 33, may be connected to any suitable 50 controlling devices. By way of example, the switch unit 106 may be connected to control a water feeder, the switch unit 106 being closed when the float 33 is in the lower position and opened when the float is in an upper position. 55 Thus, the closing of the switch unit 106 may be employed for directing feed water into the boiler until the level therein rises sufficient to raise the float and open the switch 106. The other switch unit 105 may be arranged to control the 60 burner for the boiler 1 and, according to the present invention, is preferably arranged so that when the float 33 falls to an exceptionally low level in the boiler, the switch unit 105 will be opened, thereby shutting off the burner, as by 65 shutting off the fuel supply, or otherwise controlling the same. By the adjustment of the arms 87 and 88 through the adjusting screws 94, each of the switch units may be arranged for actuation at the float position desired in order 70 to secure the required relation between the devices controlled by the switch units 105 and 106. As described, where the two units are a water feeder and a low water cutoff for the burner, the switch controlling the water feeder is so arranged 75 that normally the level 4 in the boiler is main-

tained above the position at which the switch unit 105 is opened to shut off the burner as a safety measure. In other words, the parts are so adjusted that the float 33 rises and falls to open and close the water feeder switch unit 106 5 without opening the cutoff switch unit 105, but if the liquid level 4 in the boiler 1 should fall to some predetermined excessively low position, then the switch unit 105 will be opened and shut off the burner. 10

The present invention is, of course, not limited to the use of a water feeder and burner cutoff, although that is the preferred arrangement. The switch units 105 and 106 may be connected to control any device desired. Further, if it 15 should be desired to provide a pressure responsive unit, the plug 11 may be removed and a pressure sensitive device, such as the one shown in my copending application, Serial No. 163,433, now Patent No. 2,220,144, issued November 5, 20 1940, installed in the opening 10 so that the plunger of the device will also control the position of the float 33.

The modified form of float chamber and screen construction shown in Figures 13 and 14 includes 25 a float chamber 9a having a somewhat longer neck portion 191 than the sleeve 9 shown in Figure 1. In Figure 13, the portion 191 is threaded, as at 192, so as to be screwed into a boiler wall 2. The end section 193 of the sleeve 9a 30 is provided with openings 194, like the openings 27a at the inner end of the sleeve 9 of Figure 1. The inner end of the sleeve 191 is closed by a screen disc 195 having a flange 196 adapted to closely embrace the inner end 193 of the sleeve 35 9a and a plurality of openings 197 and 198, the latter being formed by portions 198a (Figure 13) which are pressed out of the plane of the disc at 195. The flange 196 is provided with four tongues 199, each of which is formed by slitting the 40 flange and bending the stock out of the plane of the flange. One of the tongues, the lower one as indicated at Figure 14, is bent inwardly, while the other tongues are bent outwardly, and the screen 195 is assembled by inserting the lower 45 tongue into the opening 194 (Figure 13), thus locating the screen 195 in position so that the remaining three tongues 199 can be struck a blow and bent downwardly into the other openings 194, thereby securing the screen in position. As best indicated in Figure 13, the lengthening of the float chamber 39a disposes the operating parts at a somewhat greater distance from the boiler 1, and hence the float 33 is disposed at its inner end wholly within the sleeve 55 9a, and does not project therefrom as in Figure 1. However, in cases where the float 33 is shorter than indicated in Figure 1, the screen 195 may be employed for the construction shown in Figure 1, instead of the screen 28, if desired. 60

While I have shown and described above the preferred structure in which the principles of the present invention have been embodied, it is to be understood that my invention is not to be limited to the specific details shown and described above, but that, in fact, widely different means may be employed in the practice of the broader aspects of my invention. 65

What I claim, therefore, and desire to secure by Letters Patent is:

1. A low water cutoff for boilers and the like comprising a float chamber having a sleeve section at one end, said boiler having an opening to receive said sleeve section of the float chamber, a float mounted in said chamber and having 75

- its inner end extending into said sleeve section and through the opening in said boiler, the inner end of said sleeve section being apertured, and a screen for the inner end of said sleeve section, comprising a plurality of screen sections, each having a tongue adapted to be inserted in the corresponding opening in said sleeve section and a closure disc having a tongue and slot connection with said screen sections for holding the latter in assembled relation.
2. In a low water cutoff, a float chamber, a float therein having a float arm sealingly connected to and extending outwardly of said chamber, and an operating unit arranged to be actuated by said float arm and including a single switch casing, a lever pivoted thereto for movement substantially in the plane in which said float arm moves and including a yoke section receiving the outer end of said float arm and a pair of co-planar contact-actuating lever sections positioned one above the other, a first pair of switch contacts disposed in said casing and arranged to be controlled by one of said lever sections, and a second pair of switch contacts

also disposed in said casing and arranged to be controlled by the other lever section as the lever is moved about its pivot on the switch casing by the movement of said float arm.

3. In a liquid level responsive device, a float chamber, a float mounted therein and having a float arm sealingly pivoted to and extending outwardly of said chamber, and a control device carried by said chamber and including a single casing, a lever pivoted thereto for movement substantially in the plane in which said float arm moves and having a recess receiving the extended end of said float arm, whereby movement of said float in swinging said arm pivots said lever, and a pair of switch units both disposed within said casing and each having a plunger extending outwardly thereof and into engagement with said lever on opposite sides of said pivot, whereby oscillations of said lever in response to movements of the float control said switch units, said plungers being co-planar and positioned one above the other.

OSCAR F. CARLSON.
